UNITED STATES PATENT OFFICE.

JOHN B. BARTHOLOMEW, OF PEORIA, ILLINOIS, ASSIGNOR TO AVERY COMPANY, OF PEORIA, ILLINOIS, A CORPORATION OF ILLINOIS.

GANG-PLOW.

1,395,216.

Specification of Letters Patent.

Patented Oct. 25, 1921.

Original application filed October 12, 1916, Serial No. 125,288. Divided and this application filed May 4, 1917. Serial No. 166,368.

To all whom it may concern:

Be it known that I, JOHN B. BARTHOLOMEW, a citizen of the United States, residing at Peoria, in the county of Peoria and State 5 of Illinois, have invented certain new and useful Improvements in Gang-Plows, of which the following is a specification, reference being had therein to the accompanying drawing.

10 This invention relates to improvements in gang plows and especially to improvements in gang plows in which the furrow-forming elements are disks. It will be understood, however, that my invention is not necessarily 15 so limited.

In my application, Serial No. 125,288, originally filed May 15, 1913, renewed October 12, 1916, of which the present application is a division, I illustrated and described 20 a plowing mechanism in which the present improvements can be embodied, upon which application Letters Patent 1,227,237 were issued May 22nd, 1917.

The object is to provide means for supporting the frame that carries the disks 25 which will permit the disk-carrying element to be readily guided when in operation and also to be readily lifted out of plowing position. The frame has an inclined draft-bar 30 for attaching the disks in diagonal series, and it is supported at the front end upon the guiding or steering devices, and supported at the rear in such a way that it can be raised first at the rear end, and afterward 35 at the front end, on the guiding and steering devices.

Other objects will be apparent from the following description:

In the accompanying drawings I have 40 shown the embodiment of my invention which I now deem preferable. It will be understood, however, that numerous changes and modifications may be made.

Of the drawings:

45 Figure 1 is a plan view of the entire plow; Fig. 2 is a side elevation;

Fig. 3 is a rear elevation;

Fig. 4 is a fragmentary side view, partly 50 in section, of the forward right-hand supporting wheel and associated parts;

Fig. 5 is a fragmentary diagrammatic plan view of one of the rear supporting wheels and associated parts;

Fig. 6 is a fragmentary diagrammatic rear

elevation of the parts shown in Fig. 5 with 55 the frame in normal operative position;

Fig. 7 is a view similar to Fig. 6, but showing the frame in elevated position;

Fig. 8 is a fragmentary sectional view 60 taken along the lines 8—8 of Fig. 1;

Fig. 9 is a fragmentary sectional view taken along lines 9—9 of Figs. 1 and 8; and

Fig. 10 is a fragmentary diagrammatic view of the lifting cams taken from the right-hand side of the machine. 65

Referring to the drawings, it will be noted that the main frame as shown, comprises two principal parts, 1 and 2. As to the details of these frame parts, there may be variations, but in the construction shown the forward part, 1, comprises a front cross bar 3, and the side bars 4 and 5. The side bar 4 extends rearward throughout a part of its length and is then bent inward to form the diagonal member 4^a. The side bar 5 extends 70 rearward for a short distance and is then bent inward to form the diagonal element 5^a. The rear ends of the diagonal elements 4^a are joined at 6. 75

The rear frame section 2 comprises a forward member 7 which is diagonally positioned parallel to the diagonal element 4^a of the front frame. The frame section 2 also has a diagonal element 8 which is connected at its forward end to the rear end of the element 7 and which is positioned parallel to the element 5^a of the front frame. A strut or brace 9 connects the forward end of the element 7 with the rear part of the element 8. 80

The two frame sections are flexibly connected together by means of hinge devices at 10 and 10^a. 85

While I have shown in the drawings but two frame sections, it will be understood that a larger number of sections may be used 90 if found desirable. The manner of constructing and connecting such additional frame sections will be readily apparent.

Rigidly secured to the diagonal rear edge elements 5^a and 8 of the frame sections 1 100 and 2 are plowing or furrow-forming elements 11—11. As shown, these plowing elements are rotatable disks which are connected to the frame parts by means of brackets in any well-known or preferred manner, and 105 as this feature of the mechanism forms no part of my present invention, detailed description can be omitted. As shown, the

disks 11—11 are provided with scrapers 13—13, but as to this feature also, there can be variation. In fact, so far as certain features of my invention are concerned, the 5 disks may be omitted entirely and plowing elements of the moldboard type substituted.

For supporting the forward corner of the front frame section, which is opposite to the plowing elements, I provide a ground 10 wheel 14 rigidly secured to a rotatable shaft 15. This shaft 15 is mounted in a bearing 16, secured to the frame member 4 and in a bearing 17, secured to a supplementary frame member 18, which extends from the 15 front member 3, rearward, to the point of connection between the members 4^a and 5^a. For supporting the opposite forward corner 20 of the front frame section, I provide a ground wheel 19, which is loosely mounted on the axle 20 and which is or may be provided with a ground cutting flange as shown in Figs. 1 and 4. This wheel is arranged to run on the top of the land in advance of the plows and at a distance from the previously plowed ground. The axle 20 is connected with the vertical spindle 21, which is vertically slidable in a bearing aperture in a pedestal 22, secured to the frame element 5. Mechanism is provided for moving 25 the spindle 21, together with the axle 20 and the wheel 19, vertically with respect to the bracket. This mechanism will be hereinafter described in detail. For preventing the axle 20 and the wheel 19 from swinging 30 about the axis of the spindle 21, I provide the link or strut 23, which can be adjusted in length by means of the turnbuckle 24. In this way, the axle 20 can be moved, and the angle of the wheel, with respect to the 35 line of draft, can be varied as desired. The lifting of the frame relative to the wheel 19 does or may exert a pull on the link 23 to slightly swing the wheel forward, but this movement will not be of great extent and 40 will not interfere with the handling of the machine. The adjustment by the turnbuckle 24 will be such as to maintain the wheel in the desired position during plowing.

For supporting the rear part of the front 45 frame section, I provide the third ground wheel 25, which is positioned at an angle to the vertical and so located that it is adapted to travel in the furrow formed by the last disk on the front frame section. This wheel 50 25 is mounted on an axle 26 which is connected to the vertical spindle 27. This spindle 27 is slidable in a vertical bearing aperture in a pedestal 28, which is secured to the frame by means of the bracket 29. 55 In the form shown, this bracket 29 is an extension of the bracket 12 for the rear disk. As to this feature, there can be variation. Preferably the bracket 29 is reinforced by the bar indicated at 30. The spindle 27, together with the axle 26 and the wheel 25,

can be moved vertically with respect to the frame by means of mechanisms similar to that for the spindle 21. This mechanism will be described later.

The forward parts of the rear frame section 2 are supported by means of the hinges 10 and 10^a which connect them to the front frame section. The rear part of the rear frame section is supported by means of a ground wheel 31, which is mounted by means 70 of an axle 32 and a spindle 33, similar respectively to the parts 26 and 27. The spindle 33 is mounted in a pedestal 34 which is similar to the pedestal 28 and is similarly secured to the frame section. The wheel 31 75 can be moved vertically with respect to the frame section by mechanism to be described.

Secured to each of the pedestals 22, 28 and 34, is a horizontally extending arm 35 to which is pivotally connected the lower 80 end of a threaded rod 36. 37 is a yoke which is slidable on the rod 36 and which can be adjusted by means of the threaded hand wheel 38. 39 is a lever which is bifurcated at its rear end and embraces the sleeve 40 85 secured to the upper end of the spindle. The lever is pivoted to the sleeve at 41. The rear end of the lever is pivoted at 42 to the yoke 37, and a lug 43 on the sleeve 40 serves to limit the movement of the lever in one 90 direction. From the foregoing description it will be obvious that the downward movement of the forward end of the lever will cause a corresponding downward movement of the spindle and of the wheel and axle 100 with respect to the pedestal. However, as the wheel is in contact with the ground, the result will be a lifting of the pedestal and of the adjacent frame parts with respect to the wheel. The relative positions of the wheel 105 and of the frame parts can be adjusted by means of the hand wheel 38. For holding the pedestal and frame parts in lifted positions, I provide a spring held latch 44 which is adapted to engage a suitable lug on the 110 sleeve 40. Each latch 44 is held by its spring either in operative or inoperative position, as desired by the operator. When it is desired to hold the disks in elevated 115 position, the latches are manually thrown into their operative positions.

The controlling lever for the front wheel 19 is indicated, as before noted, by 39. The lever for the middle wheel 25 is indicated by 39^a. The lever for the rear wheel 31 is 120 indicated by 39^b. These levers can be operated manually by the plowman, but I prefer to also provide means whereby the levers can be moved automatically by power and moved accordingly. As to the details of this 125 lifting mechanism, there can be wide variation, but for the purpose of illustration, I have shown a mechanism which is in many respects similar to that shown and described in my earlier co-pending application for 130

gang plows, Serial No. 671,955, filed January 18, 1912.

Referring in detail to the lifting mechanism, 45 is a short jack shaft parallel to the shaft 15, upon which the ground wheel 14 is mounted. Loosely mounted on the jack shaft 45 is a sprocket wheel 46 in line with a sprocket wheel 47 on the shaft 15. A chain 48 passes over these two wheels. Secured to the sprocket wheel 46 is a notched or serrated disk 49, and adjacent to this disk and keyed to the shaft 45 is a large circular disk 50 formed at one point in its periphery with a rounded notch 51. A dog 52 is pivotally mounted on the disk 50. The head of the dog carries a laterally extending roller 53 arranged to engage with the notched periphery of the disk 49, and a spring 54 which is interposed between the hub of the disk 49 and the dog 52, tends to press the roller 53 into engagement with the disk 49. A lever 55 is pivotally mounted on the bearing bracket 56 beneath the disk 49 and carries a roller 57 adapted to ride upon the periphery of said disk. The lever also carries the roller 58 which is disposed in the plane of the dog 52. 59 is a coil spring interposed between the end of the lever 55 and an extension 60 of the bearing bracket 56, and tends to press the roller 57 radially inward against the disk 50. The upper end of the lever 55 has connected to it a rope or cord 61, which extends forward to some convenient point within the reach of the operator.

By referring to Fig. 8 it will be seen that when the roller 57 lies within the notch 51 in the disk 50, the roller 58 is in position to engage the rounded back or tail of the dog 52 and swings the dog on its pivot so that the roller 53 is withdrawn from engagement with the continuously rotating notched disk 49. If now the driver pulls on the rope 61 to swing the upper end of the lever 55 forward, the rollers 57 and 58 will be swung downward and the spring 59 will expand and cause the dog 52 to swing the roller 53 into engagement with the rotating disk 49. In this way a driving connection is effected between the disk 49 and the disk 50, so that the rotation of the former is transmitted to the latter.

The rotation of the disk 50 causes the notch 51 to be immediately moved away from the roller 57 so that when the rope 61 is released by the driver and the spring 59 tends to return the lever 55 to its initial position, such a return is prevented by the engagement of the roller 57 with the circular periphery of the disk 50. But as the disk 50 nears the end of its revolution, the roller 57 rides suddenly into the notch 51 under the action of the spring 59, and in this movement the roller 58 is caused to strike the tail of the dog 52 and to cause the disengagement of the roller 53 from the disk 49.

Thus, by a simple pull upon the cord 61, the rotation of the disk 50 is started, and at the end of a single revolution is automatically stopped. Connected to the disk 50 and to the shaft 45 is a sprocket wheel 62 which is in line with a sprocket wheel 63 on a transverse shaft 64 at the forward end of the frame. 63^a is a chain passing over the sprocket wheels 62 and 63. This shaft 64 is mounted in suitable bearings secured to the brackets 65, 66 and 67 mounted on the front member 3 of the frame. The ratio between the diameters of the sprocket wheels 62 and 63 is such that the shaft 64 is given a half revolution for every complete revolution of the shaft 45. Each of the brackets 65, 66 and 67 is formed in two parts, and between the parts of the several brackets there are mounted cams 68, 69 and 70. Pivoted to the forward outer ends of the brackets 65, 66 and 67 are levers 71, 72 and 73 which carry rollers 74, 75 and 76 adapted to engage, respectively, with the cams 68, 69 and 70. Connected to the rear end of the lever 71 is a chain 77 which extends over a suitable pulley 78 and is connected to the spindle 21. A chain 79 is connected to the rear end of the lever 72. This chain extends over suitable pulleys 80 and 81 and is connected to the lever 39^a for the wheel 25. A chain 82 is connected to the rear end of the lever 73. This chain extends over suitable pulleys 83, 84 and 85, and is connected to the lever 39^b for the rear wheel 31.

Each of the cams 68, 69 and 70 is formed with an active lifting portion 86, an inactive sustaining portion 87 and an inactive dropping portion 88. It will therefore be clear that as each cam rotates, it engages the corresponding roller to swing the corresponding lever and move the corresponding wheel downward with respect to the frame. After the movement of the lever is once effected, the lever will be held in lifted position during the next succeeding part of the rotation of the cam. Upon further rotation of the cam, the lever will be released and permitted to return to the lower position, as shown in Fig. 2.

The cams 68, 69 and 70 are regularly spaced on the shaft so that during rotation the cam 68 first comes into action, then the cam 69, and finally the cam 70. It will be understood from the foregoing description that the shaft 64 is rotated through a half revolution at each actuation of the clutch. During one half-revolution the active parts of the cams are brought into engagement with the rollers, and the three wheels 19, 25 and 31 are moved successively to cause a successive lift of the adjacent parts of the frame and of the adjacent plowing elements. At the end of the first half-revolution the rollers are still engaged by the cams, and the frame parts and plowing ele-

ments are maintained in lifted positions. During the next half-revolution the cams successively disengage the rollers and permit the levers to move and release the frame parts and plowing elements, and permit them to return successively to plowing position.

The plow, as a whole, can be hauled in any approved manner, as by means of a suitable tractor, or tractor engine. Chains 89-89 are provided for the hauling of the plow. To facilitate the turning of the plow, as a whole, at the ends of the furrows, or at the corners of a field, the wheels 25 and 31 are so mounted that they can swing laterally when the frame sections are in lifted positions. It will be noted that lugs 90 and 91 are provided which serve to hold the wheels against swinging when the frame sections are in plowing position. However, these lugs disengage the wheels when the frame sections are lifted and free movement of the wheels is therefore possible.

As before pointed out, the wheel 19 can be adjusted so as to tend to a greater or less extent to move the plow laterally and to hold the plowing elements up to their work.

What I claim is:

1. In a gang plow, the combination of a frame, a series of plowing disks connected to the frame, two wheels arranged to run on the top of the land for supporting the forward parts of the frame, the extreme front disks forming furrows outside of both land wheels, and arranged to rise and fall in horizontal parallelism with the rear disks, a wheel for supporting the rear parts of the frame, and means for adjusting one of the forward wheels angularly and holding it in adjusted position to compensate for the side thrust of the said projecting front disks.

2. In a gang plow, the combination of a frame, a series of plowing disks connected to the frame, two wheels arranged to run on the top of the land for supporting the forward parts of the frame, the extreme front disks forming furrows outside of both land wheels, and arranged to rise and fall in horizontal parallelism with the rear disks, a wheel for supporting the rear parts of the frame, means for moving the frame upward and downward with respect to the rear wheel and one forward wheel, and means for adjusting the last said forward wheel angularly and holding it in adjusted position.

3. In a gang plow, the combination of a frame comprising a plow beam, a series of plow disks attached to said beam, a ground wheel arranged at the land side of the front part of said frame and acting to support the latter and also as a source of power, a ground and frame-supporting rear furrow

wheel movably connected with the rear part of said frame, a ground and frame-supporting wheel arranged near the furrow side of the front part of the frame in advance of the plow disks and at a distance from the edge of the previously plowed ground and running on the top of the land, means for adjusting and holding the last mentioned wheel angularly with respect to the line of draft, and power connections from said power ground wheel to the said beam to lift the same at will.

4. In a gang plow, the combination of a frame comprising a plurality of plow beams, a series of diagonally and successively arranged plow disks attached to each of said beams, a ground wheel arranged at the land side of the front part of said frame and acting to support the latter and also as a source of power, a ground and frame-supporting rear wheel movably connected with the rear part of each of said beams and arranged to travel in a furrow, a ground and frame-supporting wheel arranged near the furrow side of the front part of the frame in advance of the plow disks and at a distance from the edge of the previously plowed ground and running on the top of the land, means for adjusting and holding the last mentioned wheel angularly with respect to the line of draft, and power connections from said power ground wheel to the said beams to lift the same successively at will.

5. In a gang plow, the combination of a frame, a series of plow disks diagonally and successively arranged and attached to said frame, a ground wheel arranged at the land side of the front part of said frame and acting to support the latter and also as a source of power, a ground and frame-supporting rear wheel movably connected with the rear part of said frame and arranged to travel in a furrow, a ground and frame-supporting wheel arranged near the furrow side of the front part of the frame in advance of the plow disks and at a distance from the edge of the previously plowed ground and running on the top of the land, means for adjusting and holding the last mentioned wheel angularly with respect to the line of draft, and power connections from said power ground wheel to the said beam to lift the same at will.

6. In a gang plow, the combination of a frame comprising a plow beam, a series of plow disks attached to said beam, a ground wheel arranged at the land side of the front part of said frame and acting to support the latter, a ground and frame-supporting rear furrow wheel movably connected with the rear part of said frame and arranged to travel in a furrow, a ground and frame-supporting wheel arranged near the furrow side of the front part of the frame

in advance of the plow disks and at a distance from the edge of the previously plowed ground and running on the top of the land, means for adjusting and holding the last 5 mentioned wheel angularly with respect to the line of draft, and power connections extending to said rear wheel to lift the frame at will.

7. In a gang plow, the combination of a 10 frame comprising a plow beam, a series of plow disks attached to said beam, a ground wheel arranged at the land side of the front part of said frame and acting to support the latter, a ground and frame-supporting rear furrow wheel movably connected with the rear part of said frame and arranged to travel in a furrow, a ground and frame-supporting wheel arranged near the furrow side of the front part of the frame 15 20 25 30 35
- in advance of the plow disks and at a distance from the edge of the previously plowed ground and having a ground-cutting flange running in the top of the land, means for adjusting and holding the last mentioned wheel angularly with respect to the line of draft, and power connections extending to said rear wheel to lift the frame at will.
8. In a gang plow, the combination of a frame comprising a plow beam, a series of 30 plow disks attached to said beam, a ground wheel arranged at the land side of the front part of said frame and acting to support the latter, a ground and frame-supporting rear furrow wheel movably connected with the rear part of said frame, a ground and frame-supporting wheel arranged near the furrow side of the front part of the frame in advance of the plow disks and at a distance from the edge of the previously

plowed ground and running on the top of 40 the land, an axle carrying the last mentioned wheel, a vertical pivot slidable in said frame and attached to said axle, means for adjusting said axle in horizontal planes to hold said wheel angularly with respect to 45 the line of draft, and power connections to the said pivot to lift the frame at will.

9. In a gang plow, the combination of a frame comprising a plurality of plow beams, a series of diagonally and successively arranged plow disks attached to each of said beams, a ground wheel arranged at the land side of the front part of said frame and acting to support the latter and also as a source of power, a ground and frame-supporting rear wheel movably connected with the rear part of each of said beams and arranged to travel in a furrow, a ground and frame-supporting wheel arranged near the furrow side of the front part of the 60 frame in advance of the plow disks and at a distance from the edge of the previously plowed ground and running on the top of the land, an axle carrying the last mentioned wheel, a vertical pivot slidable in 65 said frame and attached to said axle, means for adjusting said axle in horizontal planes to hold said wheel angularly with respect to the line of draft, and power connections extending to the said pivot and to said rear 70 furrow wheels to lift the frame and plows successively at will.

In testimony whereof, I affix my signature, in presence of two witnesses.

JOHN B. BARTHOLOMEW.
